UNITED STATES PATENT OFFICE.

IRVIN KLINGENBERG, OF ELGIN, ILLINOIS.

SHOE.

1,360,228.

Specification of Letters Patent. Patented Nov. 23, 1920.

Application filed January 16, 1920. Serial No. 351,755.

To all whom it may concern:

Be it known that I, IRVIN KLINGENBERG, a citizen of the United States, residing at Elgin, in the county of Kane and State of Illinois, have invented new and useful Improvements in Shoes, of which the following is a specification.

The object of my present invention is the provision of a simple, inexpensive and neatly appearing combination, whereby a shoe upper and a shoe bottom are detachably connected together so that when an upper is worn out or destroyed by acids or the like, it may be expeditiously and easily removed from the shoe bottom, and a new upper may be as readily connected with the bottom with a view to prolonging the usefulness of the bottom, and thereby contributing to economy. Likewise when the sole and heel of a shoe bottom are worn out before the upper, the upper may be supplied with a new bottom, and in that way the usefulness of the upper may be prolonged.

To the attainment of the foregoing, the invention consists in the improvement as hereinafter described and definitely claimed.

In the accompanying drawings, hereby made a part hereof:

Figure 1 is a side elevation of a shoe constructed in accordance with my invention.

Fig. 2 is a detail rear elevation of the same.

Fig. 3 is a transverse section through the shoe.

Fig. 4 is a longitudinal section of the same.

Fig. 5 is an enlarged detail view of a portion of the rim comprised in the bottom.

Fig. 6 is a detail view of the retaining loop of the improvement.

Similar numerals of reference designate corresponding parts in all of the views of the drawings.

In accordance with my invention, the sole 1 of the shoe bottom is provided adjacent to its rear end with an aperture 2, and connected to and extending entirely around the sole is a rim 3, best shown in Fig. 5. The said rim 3 may be nailed or otherwise connected to the sole 1, and when deemed expedient it may be lined with rubber, indicated by 4, or equivalent material, with a view to rendering the shoe water and dust-proof.

At 5 is a retaining loop or band that is

preferably formed of spring-metal in the general shape of a shoe bottom, and is provided at its ends with hooks 6, designed to normally rest in the aperture 2 of the sole 1, with a view to securely detachably connecting the retaining loop to the sole.

At 7 is the upper of the shoe, and at 8 is a sole that is preferably laid in the shoe and on the sole 1 when the connection of the upper to the sole 1 is completed.

It will be manifest from the foregoing that when the parts are connected in the manner described, and it is desirable for any reason to connect the sole to a new upper or the upper to a new sole, it is simply necessary to remove the hooks 6 of the retaining loop 5 from the aperture 2, when the sole 1 and the upper 7 may be expeditiously and easily separated subsequently to the displacement of the loop 5, which latter manifestly may be expeditiously and easily accomplished. Again when it is desired to fasten an upper 7 to a sole or shoe bottom equipped with my improvement, it will be apparent that the same may be accomplished with facility by arranging the edge portion of the upper against the rim 3, placing the retaining loop 5 around the edge portion of the upper, and springing the hooks 6 of the loop 5 into the aperture 2 of the sole.

My improvement is advantageous from an economical standpoint, not only because of the fact that old uppers may be inexpensively provided with new bottoms, and vice versa, but also because of the fact that a shoe bottom may be equipped with a low or high or a thick or thin upper, as the prevailing weather conditions make necessary.

It is to be understood that the rim 3 is preferably formed of sheet-metal, with its extended portion of concavo-convex form in cross-section, and slotted at intervals, as indicated by 3'.

Having described my invention, what I claim and desire to secure by Letters Patent, is:

1. The combination in a shoe, of a bottom including a sole in the rear end portion of which is an aperture, a rim connected to and extending around the sole, an upper arranged with its edge portion against the said rim, and a retaining or binding loop extending around the said edge portion of the upper and having hooks removably arranged in the said aperture of the sole.

2. The combination in a shoe, of a sole, a rim attached to and extending around the sole, an upper arranged with its edge portion alongside said rim, and a retaining or binding loop extending around the edge portion of the upper to hold the same to the rim; the sole and the retaining or binding loop having coöperating devices whereby the latter is detachably connected to the former.

3. A shoe bottom including a sole, a rim connected to and extending around the sole, and a retaining or binding loop to hold an upper to said rim; said sole and retaining or binding loop having coöperating means for the detachable connection thereof.
